(57) **CLAIM**

The ornamental design for a surgical apparel as shown and described.

DESCRIPTION

1. Surgical apparel

1.1 : Front

1.2 : Back

1.3 : Top

1.4 : Bottom

1.5 : Left

1.6 : Reference perspective view

1.7 : Reference back view

The right view is omitted since the claimed features depicted in the left view appear symmetrically in the right view; the evenly-spaced broken lines in the figures form no part of the claimed design; the dash-dotted broken lines denote the boundaries of the claimed design and form no part thereof; discontinuous thin lines shown in each view represent the shape of all surfaces of the three-dimensional aspects of the present design; the reference perspective view shows the present product with a zipper in an exposed state; the present product serves as a surgical apparel for healthcare workers; the essential feature of the present design resides in the shape of a collar and a back part depicted in solid lines; the present product is made of cloth, non-woven fabric, paper, plastic or vinyl materials.

1 Claim, 7 Drawing Sheets
